FIRE EXTINGUISHER

Filed Oct. 10, 1923

UNITED STATES PATENT OFFICE.

LUTHER ROBINSON, OF ELDORADO, KANSAS.

FIRE EXTINGUISHER.

Application filed October 10, 1923. Serial No. 667,642.

To all whom it may concern:

Be it known, that I, LUTHER ROBINSON, a citizen of the United States, residing at Eldorado, in the county of Butler and State of Kansas, have invented certain new and useful Improvements in Fire Extinguishers; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a fire extinguisher and the primary object thereof is to provide a novel form of portable fire extinguisher in which a fluid may be retained within a casing or cylinder to be discharged therefrom by gas pressure generated by two separate mediums which combine to form gas to create the pressure within the casing.

Such devices generically have been provided before my invention but I have made a simple novel form of portable fire extinguisher in which the means for operating the extinguisher is both simplified and improved in operation.

One of the novel features of the invention is a renewable cartridge containing the elements for generating the gas. Another important feature is the operating mechanism. All of these will be apparent by reference to the following description in connection with the accompanying drawings, in which

Fig. 1 is a vertical, longitudinal, sectional view through a fire extinguisher constructed in accordance with my invention and with the parts in normal positions.

Fig. 2 is a similar view showing the parts in position to permit generation of gas on the liquid, and

Fig. 3 is a fragmentary, perspective view of the renewable cartridge.

The invention is shown as comprising an outer shell or casing 1 adapted to contain extinguishing liquid, having a removable cover 2 having threaded connection with the shell or casing 1 at 3. The cover 2 has a collar 4 in the form of an elongated tube,

the upper end of which projects above the cover 2 and the lower end of which projects below the cover 2. The upper end of the collar 4 receives a packing gland 5 through which projects a plunger stem 6. The plunger stem has a hollow upper portion 7 provided with an inlet hole or port 8 and an outlet nozzle 9. The lower end of the stem projects through the web 10 of the collar which combines with the upper portion of the collar to form a chamber 11 with which the opening 8 may communicate to connect the hollow portion of the stem 6 with the discharge tube 12 connected to the collar and communicating it with the interior of the casing 1.

The lower portion of the collar 4 also carries a nipple 13 threaded thereinto and provided with a packing 14. The lower end of the nipple 13 may receive the threaded collar 15 of the removable cover 16 carried by the gas chamber casing 17. The gas chamber casing is closed when the cover 16 is in place and it is adapted to receive a cartridge containing the chemicals to form the gas.

The cartridge may consist of a cylinder or tube 18 containing an acid container or bottle 19. The acid is confined within the bottle 19 by the disruptible cover 20 which may consist of a thin sheet of lead or similar material which will not be attacked by acid. Above the bottle 19 is a charge of soda 21, in which is embedded a hollow plunger 22 having a cone-shaped bottom 23 which, when pressure is applied to the plunger, will disrupt the cover 20 to allow the soda to combine with the acid in the bottle 19. In order to insure the combining of the soda with the acid, I have made the plunger hollow and provided it with a screenlike wall 24 of reticulated material so that it may contain some of the soda. The stem 27 of the plunger is adapted to receive pressure from the head 26 on the end of the stem 6.

It will be observed that the head 26 is of greater diameter than the stem 6 and that the opening in the collar 15 is, therefore, of greater diameter than the stem 6. Consequently, when pressure is applied to the

disk-shaped end 26 of the stem 6, the pressure will be communicated to the plunger 22.

I prefer to make the plunger 22 of wood so that it will be non-corrosive.

- 5 When pressure is applied to the plunger 22, the cone-shaped end 23 will disrupt the sheet 20 and allow the plunger to pass into the acid contained in the bottle 19; the soda and acid will combine to cause chemical action to start, which will, in turn, cause the acid to splash out into the space above the bottle 19 and attack the soda 21 contained therein so that the chemicals in the cylinder 18 will combine to form gas.
- 15 Since the movement of the stem 6 is enough to move the head 26 inwardly away from the cover 16 and in view of the fact that the opening in the cover 16 is of greater diameter than the stem 6, it is apparent that 20 when the plunger 22 is driven into the bottle as shown in Fig. 2, there will be a space around the stem 6 through the cover 16. Therefore, gas can pass into the nipple 13 and escape through the openings 28 into the 25 casing 1. The same movement results in causing the port or opening 8 to register with the chamber 11. Therefore, the pressure of the gas on the liquid will force the liquid through the tube 12 into the chamber 11, through port 8, through the hollow portion 7 of the stem 6 and through the nozzle 9.

When the gas has discharged all of the liquid the extinguisher will be depleted. Then it will be necessary to recharge the 35 same. This can be easily accomplished by removing the cover 2, taking off the gas chamber casing 17, dumping out or removing whatever remains of the cartridge 18, that is, the bottle 19 and the plunger 22, and the cartridge shell can be removed, and a new cartridge dropped into place.

The stem 6 having been restored to the position shown in Fig. 1, the cap 16 is screwed in place so that the parts are re-established as shown in Fig. 1.

The cartridges may be kept in stock as complete renewals and ordinarily, they will be provided with covers 29, the covers being removed, of course, prior to introduction into the casing 17. Of course, each time the cartridges are renewed, the casing 1 must be replenished with the liquid, after which the cover 2 is screwed in place.

It will be apparent that the device is quite 55 simple in construction, that it may be recharged in a safe and expeditious manner, and that the chemicals for creating the gas pressure will remain intact over long periods because liability of them attacking corrosive surfaces or combining will be entirely eliminated since the acid will not attack the glass nor the lead, nor will the dry soda attack the cardboard or fibrous container 18.

When the parts are in the position shown 65 in Fig. 1 there will be no difficulty in starting the device to operate because it will be only necessary to ram the end 28 against the wall or any abutment so that the conical end 23 of the plunger 22 will disrupt the cover 20.

The devices may be made for various capacities the exact form and minor details of construction are not important so long as the novel features of the invention are 75 incorporated.

What I claim and desire to secure by Letters Patent is:

1. A fire extinguisher comprising a casing having a removable cover with a depending collar, a nipple on the end of the collar, a gas chamber casing connected to the nipple, a plunger stem projecting through the cover and having a head projecting through an opening in the gas chamber casing, the head being of greater diameter than the stem, the stem having a hollow portion provided with an inlet and an outlet, the inlet communicating with a chamber formed by the collar carried by 90 the cover, the outlet in the stem being on the outside of the casing, and a pipe communicating with the chamber and with the interior of the casing, the gas chamber casing being adapted to contain chemicals rendered active by longitudinal movement of the plunger.

2. A fire extinguisher comprising a casing having a removable cover with a depending collar, a nipple on the end of the 100 collar, a gas chamber casing connected to the nipple, a plunger stem projecting through the cover and having a head projecting through an opening in the gas chamber casing, the head being of greater diameter than the stem, the stem having a hollow portion provided with an inlet and an outlet, the inlet communicating with a chamber formed by the collar carried by 105 the cover, the outlet in the stem being on the outside of the casing, a pipe communicating with the chamber and with the interior of the casing, a cartridge in the gas chamber casing comprising a tube, an acid containing bottle in the bottom of the tube, a disruptible cover, a soda charge above the bottle, and a soda-containing element 110 in line with the plunger and movable thereby to disrupt the cover in the bottle.

3. A cartridge for recharging fire extinguishers comprising a tube, an acid containing bottle in the bottom of the tube having a disruptible cover, a charge of soda above the bottle, and a soda-containing head embedded in the soda charge.

4. A renewable cartridge for fire extinguishers comprising a tubular casing, a liquid-containing bottle in the bottom of the

casing, a solid material above the bottle, a disruptible cover separating the solid material from the liquid, and a plunger embedded in the solid material.

5. A renewable cartridge for fire extinguishers comprising a tubular casing, a liquid-containing bottle in the bottom of the casing, a solid material above the bottle, a

disruptible cover separating the solid material from the liquid, and a plunger embedded in the solid material, said plunger having a space for carrying some of the solid material into the bottle. 10

In testimony whereof I affix my signature.

LUTHER ROBINSON.
